UNITED STATES PATENT OFFICE.

SAMUEL A. RUSSELL, OF RIVER FOREST, ILLINOIS.

BED.

Application filed September 24, 1919. Serial No. 325,984.

To all whom it may concern:

Be it known that I, SAMUEL A. RUSSELL, a citizen of the United States, residing at River Forest, in the county of Cook and State of Illinois, have invented a certain new and useful Improvement in Beds, of which the following is a specification.

This invention relates to beds and has for its object to provide a new and improved bed which can be taken apart and the several parts assembled so as to occupy a small space either for storage or transportation and can be easily and quickly assembled for use. The invention is illustrated in the accompanying drawings, wherein—

Fig. 1 is a side elevation showing one form of bed embodying the invention;

Fig. 2 is a plan view of the device shown in Fig. 1;

Fig. 3 is an end view of the bed shown in Fig. 1;

Fig. 4 is a sectional view on line 4—4 of Fig. 2;

Fig. 5 is a sectional view taken on line 5—5 of Fig. 4;

Fig. 6 is a perspective view showing the intermediate support and the connecting pieces pivoted thereto;

Fig. 7 is a perspective view showing a portion of one of the end posts and the connecting pieces pivoted thereto;

Like numerals refer to like parts throughout the several figures.

In carrying out the invention I provide four corner posts, two posts at one end and two posts at the other end, which may be made of any suitable material. The end posts at each side are connected together so that during the assembling of the parts they may be moved with relation to each other, that is so that they may be brought closer together and then moved farther apart. In the construction shown this result is secured as follows: Connecting pieces 3 and 4 are provided which connect the posts 1 and 2 with the intermediate post 5. This connection is preferably such that when the intermediate post is moved longitudinally in one direction the posts 1 and 2 will be moved toward each other and when the intermediate post 5 is moved back the end posts will be moved farther apart. In the construction illustrated this result is secured by pivoting the connecting pieces 3 and 4

with the end posts and intermediate posts. 55 A simple construction for this purpose is illustrated wherein plates 6 are connected one on each side of post 1 and fastened thereto by fastening devices 7. These plates project beyond the post as illustrated in 60 Fig. 4. The connecting piece 3 is placed between these plates and pivoted thereto by means of the pivot 8. The intermediate post 5 is provided with side plates 9 which are attached thereto by the fastening devices 65 10 and which project on both sides thereof. This intermediate post is preferably short and the plates 9 may be formed with an integral piece extending across the top of the post. The connecting piece 3 is pivoted 70 between the plates 9 by the pivot 11. The connecting piece 4 is pivoted between the plates 9 by the pivot 12. The post 2 is provided with the plates 13 which are fastened thereto by the fastening devices 14 and which project on one side thereof and the connecting piece 4 is pivoted 75 between them by the pivot 15. I may also provide braces 16 and 17 between the end posts and the intermediate posts, said braces 80 being pivoted to the posts.

The supporting device upon which the occupants are supported may be of any suitable material, preferably flexible, so that it may be rolled up, such as canvas woven 85 wire, springs or the like. This support 18 is fastened to the end pieces 19 and 20 which may be of any suitable shape and which are herein shown as consisting of angle shaped pieces. The side portion of each 90 angle shaped piece is provided at each end with a projection 21 by means of which it is connected with the end posts. A simple form of connection is illustrated in the drawings, wherein the projections 21 are 95 provided with notches or openings 22 into which fit pins or projections 23 on the posts. It will be seen that when these pins are inserted in these openings, the supporting piece will be supported in position and be 100 held at a distance from the ends of the posts so as to support the occupants above the surface upon which the posts rest.

One of the difficulties with a construction of this kind is to easily and quickly secure the proper tension of the support 18 so that it will not sag an undue amount when in use. In the construction shown this tension 105

is easily and quickly secured as follows: Before placing the projections 23 in the openings 22, the intermediate posts 5 are lifted or moved longitudinally so as to bring the posts 1 and 2 closer together. The support 18 is then placed in position, the end pieces 19 and 20 being simply pushed down so that the pins 23 enter the openings 22. The intermediate posts are then moved back 10 to their initial position so as to straighten out the connecting pieces 3 and 4, and thus push the posts 1 and 2 farther apart so as to stretch the support 18 and secure the proper tension thereon. When the intermediate post is moved the predetermined amount, the connections 3 and 4 are substantially in alignment so that there is no tendency to buckle, and the support 18 is held in this stretched or tensioned position. 15 The tension desired may be secured by regulating the length of the various parts, and the movement of the posts 1 and 2 to and from each other. I prefer to provide the end pieces 19 and 20 of the support with braces 24 which may be pivoted to the end pieces and then connected with the posts 1 and 2. This connection may be any suitable connection. As herein shown the braces 24 are provided with notches 25 which slip over pins 26 in the posts 1 and 2. A single or double bed as desired may be provided. 20

In the drawings I have shown a double bed wherein there is an additional support 18^a located above the support 18 and having 25 end pieces 19^a and 20^a similar to the support 18. In this construction the intermediate post 5 is provided with an extension piece 27 which rests upon the top thereof and which may be provided with a pin 28 which enters a hole in the post 5. Connected with the extension piece 27 are the connecting pieces 29 and 30. These connecting pieces are preferably pivoted to the extension 27 in any desired manner. They may be pivoted between plates 31 similar to those between which the connecting pieces 3 and 4 are pivoted. The ends of the connecting pieces 29 and 30 as herein shown are provided with pins 32 which enter holes in the posts 1 and 2. In connecting the support 18^a with the posts 1 and 2, extension 27 is moved so that the upper ends of the posts may be brought closer together. The end pieces 19^a and 20^a are then moved to a position 30 where the pins 23^a enter the notches 22^a. The upper ends of the posts 1 and 2 are then moved apart by moving the extension 27 downwardly so as to straighten out the connections 29 and 30. The bed may be made out of any desired material, either metal or wood or the like, and where it is to be transported, as for example to be used by automobiles and other travelers, the posts may be made of wood so as to be made 35 lighter.

When it is desired to take down the bed so as to store it or transport it, this may be done as follows. The extensions 27 are moved up so that the upper ends of the posts 1 and 2 may be brought closer together, 70 and then the end pieces 19^a and 20^a are moved upwardly so as to disconnect the pins 23^a from the slots 22^a. The support 18^a may then be removed and rolled up into a compact roll. The extensions 27 are then 75 removed and the connecting pieces 29 and 30 pivoted thereto are folded down along the extension pieces. The intermediate posts 5 are then moved upwardly to permit the end posts to move toward each other to 80 reduce the tension on the support, whereupon the support 18 is removed from the posts and rolled up into a compact roll. The intermediate posts 5 are then moved so as to fold the end posts and intermediate posts, 85 the connections 3 and 4 and the braces 16 and 17 together into a compact form. The several parts are then placed together, forming a compact device which may be carried either in a roll of flexible material which 90 forms a protecting cover, or in a box. It will thus be seen that the device can be taken down and put into compact form so that it may be carried at the back of a saddle by a man on horse back, or carried 95 in an automobile or stored in a very small space for transportation or storage purposes.

It will thus be seen that the device can be easily and quickly taken down and set up, the entire occupation occupying only a few 100 minutes. It is of course evident that the connecting pieces 3 and 4 and 29 and 30 may be arranged so that they will not be in exact alignment but so that their inner ends will be a little lower than their outer ends. This 105 will insure their being locked while in this position. The posts 5 being on the ground, floor, or other support will prevent any further movement in that direction. It will further be noted that the tension is placed 110 upon the support for the occupants, by moving the intermediate posts 5 and extension 27 downwardly, and that when the occupant is resting on the support his weight tends to hold these parts down so that there can be no accidental movement thereof.

The device may be used either as a single or a double bed. It may also be used as a cot.

I claim:

1. A bed comprising end posts, a support for the occupant, said support provided at its ends with cross pieces, said cross pieces having portions which project across between the end posts and having projecting pieces which project across the outer faces of the end posts, openings in said projecting pieces, projections on said end posts which fit into said openings, pivotal connections between the end posts at one end and the 120

end posts at the other end, said pivotal connections arranged to be moved to an angular position to bring the posts closer together while the support is being connected therewith, and means for straightening out said pivotal connections so as to move the end posts away from each other, and hold them in fixed relation to each other so as to stretch the support and hold it in its stretched position.

2. A collapsible bed comprising end posts, intermediate posts, pivotal connections between said end posts and said intermediate posts, extensions connected with said intermediate posts but adapted to be separate therefrom, connecting pieces pivoted to said extensions and detachably connected with said end posts, a plurality of supports for occupants connected with said end posts and located in different vertical planes.

3. A collapsible bed comprising end posts, intermediate posts, extensions connected with said intermediate posts, connecting pieces between said end posts and intermediate

posts and pivotally connected with said extensions, and a support for the occupant carried by said posts.

4. A bed comprising end posts, intermediate posts, two connecting pieces at each side of the bed pivotally connected to said end posts and projecting toward the intermediate posts, the adjacent ends of said connecting pieces at each side of the bed being both pivotally connected with the intermediate post at that side of the bed, whereby the end posts may be moved toward and from each other, a support for the occupant and cross pieces with which the ends of the support are connected, said cross pieces detachably connected with the end posts.

In testimony whereof, I affix my signature in the presence of two witnesses this 23d day of September, 1919.

SAMUEL A. RUSSELL.
